CHARLES F. KETTERING AND WILLIAM A. CHRYST, OF DAYTON, OHIO, ASSIGNEES TO
THE DAYTON ENGINEERING LABORATORIES COMPANY, A CORPORATION OF OHIO.

ENGINE-STARTING SYSTEM.

1,250,188

Specification of Letters Patent.

Patented Dec. 18, 1917.

Application filed September 18, 1913. Serial No. 789,641.

To all whom it may concern:

Be it known that we, CHARLES F. KETTERING and WILLIAM A. CHRYST, citizens of the United States of America, residing at Dayton, county of Montgomery, and State of Ohio, have invented certain new and useful Improvements in Engine-Starting Systems, of which the following is a full, clear, and exact description.

10 This invention relates to electric starting and generating devices, in which the electric machine has a double wound armature and a brush lifting switch, such for example as shown in the applications of C. F. Kettering, Serial No. 721,237, filed September 19, 1912; and Kettering and Chryst, Serial No. 778,934, filed July 14, 1913.

It is among the general objects of the present invention to improve upon the constructions shown in the applications referred to, and more particularly to provide different sets of field windings for the electric machine, to be used selectively with the different armature windings to secure the desired results in the way of the cranking movement, the generating operation, and the slow initial starting movement of the electric machine.

And with these devices are combined the arrangements of the brush lifting switch for the motor armature circuit, and an additional, outside switch, for controlling or selecting the desired circuit arrangements to perform the different functions referred to.

35 With these general objects in view, and for the purpose of accomplishing the various desired results by novel arrangement and combination of the elements of the system, a preferred form of embodiment of 40 these improvements is shown in the accompanying drawings and described in detail hereinafter.

Referring to the drawings:

Figure 1 is a diagrammatic view of the 45 electrical connections and circuits embodied in the present invention, the brushes being shown in their normal position, that is, for the generating operation of the machine; and Fig. 1^a is a similar view, but with the 50 brushes shown as shifted for the motor cranking operation.

Fig. 2 is a top plan view of a chassis of

an automobile including the engine. This view illustrates a preferred form of combining the starting device with the engine. 55

Fig. 3 is a detail top plan view partly in section of the starting device, clearly showing the controlling mechanism in combination with the shiftable gearing and cut-out relay at one end of the starting device, and 60 the brush lifting mechanism at the opposite end thereof.

Fig. 4 is a fragmentary detail view in section of an engine having a starting device applied thereto, showing the gearing 65 thereof in starting position.

Fig. 5 is a detail sectional view of the electric machine applied to an engine having a nonmagnetic crank case.

Fig. 6 is a view in front end elevation of 70 the electric machine.

Fig. 7 is a view similar to Fig. 6, with the end casing removed to more clearly illustrate the arrangement of the commutator brushes relative to the armature. 75

Fig. 8 is a detail view of the motor brush and its commutator, said brush being held in its normal circuit breaking position by the controlling mechanism.

Fig. 9 is a view similar to Fig. 8, showing 80 the brush in position to close the motor circuit, for starting purposes.

Fig. 10 is a detail view of one of the motor and one of the generator brushes mounted on a common supporting element 85 or plate which also constitutes a cover for one of the openings in the front end housing.

Referring to the drawings and more especially to Figs. 2 to 10 inclusive, the numeral 20 designates the side frames of the chassis while the numeral 21 indicates the engine, provided with a fly wheel 22, having gear teeth 23 cut in its periphery.

The type of chassis and engine construction shown in the present instance is similar 95 to that manufactured and placed on the market by the Buick Motor Car Company.

The dynamo electric machine is designated by the numeral 24 and is adapted to be driven as a generator during the normal 100 operation of the engine, by means of the timing gears 25, which transmit motion to the generator through the shaft 26, as is clearly shown in Fig. 2.

The location and arrangement of the dynamo electric machine is similar in certain respects to that described, illustrated and claimed in the patents and applications above referred to.

This machine is controlled as to its status as a motor, or generator, by means of a controlling mechanism which comprises the main operating member or pedal 27, suitably 10 mounted on the rod 28, which extends transversely between the side frames 20, said rod also passes through and is fixed to the sleeve 28', to which the pedal is connected. As is shown in the present instance, the sleeve 28' 15 also has a projection 30, which is pivotally connected with the rod 31. This rod 31 extends forwardly and is connected in any suitable manner with the rod 32, one end of which projects outwardly from the rear end 20 housing 33 of the dynamo electric machine. This supplemental shaft or rod 32 extends from the dynamo electric machine parallel with the armature thereof, but suitably spaced apart therefrom.

25 The front end of this rod is beveled as at 34, said beveled portion resting adjacent to a roller or other suitable friction reducing element 35, carried by the brush holder 36 of the movable motor brush 37.

30 Any suitable bearings for the shaft 32 may be provided in the end housings and main frame of the electric machine, so as to assure the alinement of said rod at all times. The rear end housing 33 of the electric machine, as will be clearly seen from Figs. 35 2, 3 and 4, is divided into suitable compartments, in one of which is located the shiftable coupling gearing 38, which comprises the pinions 39 and 40, mounted upon the 40 stub shaft 41. A projecting arm 44, carried by the rod 32, is connected with the shiftable gearing 38, in such a manner that when the rod 32 is moved longitudinally, a corresponding movement of the gearing 38 45 will be effected.

By referring to Figs. 2 and 3, it will be seen that the pinion 39 normally rests adjacent to but out of engagement with the teeth 23 formed on the periphery of the fly 50 wheel, while the pinion 40 rests adjacent to but out of engagement with the pinion 42, carried on the armature shaft 43 of the electric machine.

As has been explained in the patents and 55 the co-pending applications heretofore referred to, the space between the pinion 40 and the armature pinion 42 is less than the space between the pinion 39 and the fly wheel gearing, when in normal position. 60 This is so that when the gearing is shifted, the pinion 40 will engage with the armature pinion, previous to the engagement of the pinion 39 with the fly wheel gearing.

It will of course be understood that the 65 end housing 33 is provided with an open

side, so that the pinion 39 may be readily moved into and out of engagement with the fly wheel gearing.

As has been stated heretofore, the rear end housing 33 is divided into separate compartments, one of which contains the shiftable gearing just described, while another of the compartments contains certain of the switch elements which control a part of the electrical connections of the system, which 70 will be described hereinafter.

One of these switch units comprises the contact plates 45, 46 and 47, respectively, so arranged that the plates 45 and 46 will be normally in closed position. These plates 80 form part of the generator circuit which, as will appear hereinafter from the description of the electrical connections, will be normally a closed circuit in so far as these contacts are concerned and only opened at 85 these contacts at such times as it is desired to employ the system for starting purposes.

The plate 47, which is mounted adjacent to the rod 32, is provided with an insulated lug or projection 48 which extends into the 90 path of the cams 49 and 50, carried by and fixed to the rod 32.

From the above description, it will be noted that when the pedal 27 of the main operating mechanism is depressed by the 95 operator, the rod 31 will be drawn rearwardly, thus in turn moving the shaft 32 in a similar direction. The first operation which will be effected by the movement of the pedal 27, will be the closing of the contact plates 47 and 45, this being effected by the cam 49 engaging with the insulated lug 48.

This initial movement of the operating 105 pedal is for the purpose of producing the slow initial rotation of the electric machine, for the purpose of facilitating enmeshment of the gears. In such initial position, the shaft 32 and its cam carrying head occupies a position intermediate between the normal or generating position of Fig. 1, and the shifted or motor cranking operation shown in Fig. 1A, and the general purposes of such slow initial movement are referred to in the 110 patents and applications mentioned above.

By referring to Fig. 3, it will be seen that the projecting element 44 will not effect a movement of the gears at this time, inasmuch as there is a certain amount of lost motion permitted, previous to its shifting 120 the gearing 38.

As soon as the contact plates 47 and 45 are brought together, a circuit will be closed through the generator windings, which will effect a slow initial rotation of the armature, so that when the rod 32 is further moved rearwardly, the pinion 40 will readily engage with the armature pinion 42, which will of course transmit a rotating 125 movement to said gearing and thus facilitate 130

the coupling up of the pinion 39 to the gear teeth of the fly wheel.

The arrangement of the circuits above referred to will be fully described hereinafter.

The continued movement of the operating pedal and its connected shaft 32 is adapted to connect up the electric motor to the fly-wheel of the engine for cranking purposes. That is, the coupling gearing 38 thereupon moves into its coupling position, in which the gear wheel 40 meshes with the armature pinion 42, (see Figs. 3 and 4), and the gear wheel 39 meshes with the teeth on the fly-wheel of the engine. This coupling movement is an accompaniment to the slow initial starting movement referred to, which slow initial movement facilitates the enmeshment of the gearing.

The parts are now in position ready for the cranking operation, so that the further movement of the operating pedal and its connected rod 32, is adapted to operate the necessary switches for the motor cranking operation.

In Fig. 1^A, the rod 32 is shown shifted to its left hand position, wherein the outer cam 50 still further depresses the contact strip 47, so that it not only makes contact with the strip 45, but also separates the strip 45 from the contact strip 46. The effect of this is to break the generator circuit for the motor cranking operation.

At the same time, as shown in Figs. 3, 7 and 8, the beveled end 34 of the continuation of the rod 32, (sliding to the right as shown in Fig. 3), will permit the spring pressed brush holder 36 to drop down, under influence of the spring 81. This is the commutator brush of the motor cranking circuit, as shown in Figs. 1 and 1^A; and when dropped down to the position shown in Fig. 1^A, this motor brush 37 then makes contact with the motor commutator 52 and the motor armature windings.

This operation will effect the closing of the motor circuit, so that the electric machine will operate with a high torque effect, to crank the engine for starting purposes.

Now, if the mechanical connections between the motor and the engine are maintained after the engine becomes self-actuating, the tendency would be to have the engine rotate the motor at an extremely high rate, due to the reduction gearing which comprises the mechanical connections.

As has been disclosed in the co-pending applications heretofore referred to, a one-way clutch mechanism is embodied in the gear wheel 40, so that at any time that the engine tends to drive the motor, this one-way clutch will be brought into effect, so as to substantially disconnect the motor from the engine.

Inasmuch as this clutch structure is described in detail in the aforementioned co-

pending applications, it is not shown or described in detail in the present application.

By referring to Fig. 5, one of the preferred embodiments of the dynamo electric machine is clearly shown.

In certain types of engines, such for instance as are employed as power plants in automobiles of the Buick type, the crank case or certain parts of the engine frame are constructed of nonmagnetic material, such as aluminum or its equivalent. It is well known that in electric machines, it is advisable to provide a base for the machine which is of nonmagnetic material, so that the magnetic path through the frame of the machine will be interrupted and the flux will be diverted across the armature.

The construction just referred to, is described and claimed in a co-pending application filed as a division of the present application, and bearing Serial No. 81,410, filed March 1, 1916.

The general structure referred to is preferably as follows:

The electric machine, as will be clearly seen from Fig. 5, comprises the side frames 55 and 56, connected together at their upper ends by means of the transverse bar or block 57, which is connected by any suitable fastening means 58. This bar forms a support for the field coil 59, which in the present invention contains both the generator and motor field windings.

The free end of the frame 56 terminates in an enlargement which constitutes one of the pole pieces of the machine, while the frame 55 also has an enlarged portion which constitutes the opposite pole piece. The free ends of the side frames are so arranged that a space is left therebetween.

In mounting the electric machine on the crank case of the engine, a portion thereof tends to extend into this space between the ends of the frame, and thereby interrupts the magnetic path through the frames and thus diverts the magnetic flux across the armature.

Any suitable arrangement may be made for inclosing the top of the machine, as by the cover 60.

The electric machine embodied in the present invention is provided with a front end casing which has an opening at one side thereof, which is adapted to be closed by means of a cover plate 70. This cover plate is so arranged that it carries the lower motor commutator brush 72 and the lower generator commutator brush 75. The term "lower" in the present instance is used with reference to Figs. 7 and 10.

The motor brush 72 in this instance comprises the holder 71 and the brush element 71^A, said holder being pivotally mounted in any suitable manner on one side of the lug 73. This brush is normally held in position

to engage the commutator by means of the spring 74, and is provided with an extension 73^a, which prevents the brush holder from movement toward the armature after the brush has worn down to a predetermined point.

The generator brush comprises the brush element 75, carried by the holder 76, mounted on the opposite side of the lug 73, while the spring 78 is so positioned as to normally maintain the said brush in contact with its commutator.

Now, if at any time it is desired to repair or replace one of these brush units, it is only necessary to remove the plate 70, by loosening the means which holds it in applied position.

The upper set of brushes, as shown in Fig. 7, comprise the motor brush 37, secured 20 to the holder 36, which in turn is pivotally mounted on the plate 79. The rear end of the holder is provided with a roller or other friction reducing member 35, as has been explained heretofore, and normally rests in 25 such a position that it will be engaged by the rod 32, and held in a raised position, away from the motor commutator of the armature, and against the tension of the spring 81.

30 Any removable cover means may be applied to the front end housing to inclose the upper brush structure.

The electrical connections included in the present invention are clearly shown in Fig. 35 1 and Fig. 1^a and will now be described.

It will be appreciated that when the machine is employed for starting purposes, a high torque effect is required, in order to efficiently crank or turn over the engine to 40 permit the same to become self actuating. This high torque effect is secured in the present instance by supplying current of comparatively high amperage, at a relatively low voltage, to certain of the armature and field windings.

On the other hand, it is equally desirable that the machine, when operating as a generator, shall supply current of such an amperage and voltage as will be proper to 50 charge the battery.

It is advantageous to employ a separate set of windings and electrical connections, inasmuch as the proper wattage for charging a battery employed in this type of system is usually (other conditions being as they are in the present case) much lower than the wattage which the battery discharges to the motor for starting purposes.

It is also highly desirable that the generator be brought up to a point of where its voltage is sufficient to effect the charging of the battery as quickly as possible, after it has commenced to operate and at the lowest speed possible.

65 In carrying out these objects, the motor

circuit for cranking comprises a low resistance motor armature set of windings for cranking, and a separate set of armature windings, of higher resistance, for generating, as described in the applications at 70 referred to.

In addition, three separate sets of field windings are used, one a heavy series field winding for the motor cranking operation; the second a shunt field winding for the 75 generating operation; and the third an auxiliary series field winding, wound oppositely to the shunt field winding, to give the well known differential effect for regulation of the generating current.

80 Other devices for further regulation of this current are also included as hereinafter referred to.

Furthermore, the switch arrangements are of such character that the shunt field set 85 of windings, above referred to, are used accumulatively with the first mentioned set of series field windings of the cranking circuit, so that during the cranking operation, the field is energized by the joint effect of the 90 heavy series field winding and the shunt field winding.

By referring to Fig. 1, it will be supposed that the engine to which the starting system is applied is at rest and that it is 95 desired to start the same.

The electrical connections will be in the position shown in Fig. 1, and the sequence of operations which will complete the cycle 100 of operation of the controlling mechanism will be as follows: Upon an initial movement of the rod 32, contact plates 47 and 45, will be brought together, thus closing the circuit so that current will flow from the accumulator, 90, which is preferably of the storage 105 battery type, through the wire 91, to the plate 47, via wire 92. From this plate 47, it will proceed through the plate 45, where a portion of the current will branch off through the contact plate 46, through the 110 wire 93, and across the generator brushes and therefore through the generator-armature windings to the wire 94, thence to the ground connection 95, and back to the battery 90, via wire 96.

115 The remainder of the current will proceed via wire 97, branch wire 98, through the winding 99, which ordinarily constitutes the shunt winding of the generator, the ground connection 95, through the wire 100 120 and thence back to the battery via wire 96. This flow of current will effect the operation of the machine as a motor, at a reduced speed.

125 A continued movement of the above mentioned rod 32, it will be recalled from the previous description, will couple the starting device up to the engine for starting purposes, by the shifting of the coupling gear 130 38 into engagement with the armature

pinion and the fly wheel of the engine. This continued movement of the rod will also open the contact plates 45 and 46, so that the circuit across the generator brushes will be broken, while the circuit through the shunt field winding will be maintained.

However, at the end of this movement of the rod 32, it will release the movable motor brush 37, so that the spring 81, will force the 10 same into contact with the motor commutator and thus close the following circuit: from the battery 90, through the wire 91, through the series winding 101, the brush holder 36, brush 37, across the armature, that 15 is, through the motor-armature windings, through the opposite motor brush 72 to ground, via wire 102, and back to the battery, via wire 96.

As above stated, the shunt field circuit 20 is closed at this time, and as this is the position for the motor cranking operation, it is obvious that the series field winding and shunt field winding are assisting each other in field energization, during this period of 25 motor cranking.

It will also be noted, that, as appears from the applications above referred to, there are two separate sets of armature windings, the generator windings and the motor windings. The generator-armature windings are used for the slow initial movement to facilitate the coupling referred to,—and are likewise used for the regular generating operation,—and the motor-armature windings 35 are used for the engine cranking operation.

The pair of generator brushes 75 remain in contact with the commutator bars of the generator-armature windings; one of the motor brushes, viz. 72, remains in contact 40 with the commutator bars of the motor-armature, but the other motor brush 37 is carried by the movable arm 36, so as to constitute a means for making and breaking the motor circuit for the engine cranking 45 operation, thus constituting a brush lifting switch.

As also explained in the applications referred to, the motor-armature windings are preferably of few, heavy turns to give high 50 wattage and torque for cranking, while the generator-armature windings are of greater number of turns and higher resistance for the charging condition.

Now, as soon as the engine becomes self 55 operating, the operator releases the pressure on the pedal 27, which in turn will permit the rod 32, to be brought back into its normal position, by means of the spring or other suitable mechanism 103. This return movement of the rod 32 to its normal position, 60 will again raise the motor brush 37 out of contact with its commutator and thus the circuit just described will be broken, so that the machine will no longer operate as a series 65 motor. However, the contact plates 45 and

46 will assume their normal position to close the generator circuit, while the plates 45 and 47 will be spaced apart, so that the initial circuit described as being adapted to pass current through the shunt winding of the 70 generator, to operate the same as a motor, will be broken.

It is now considered that the engine is self-actuating and operating under normal conditions. The electric machine will then be 75 driven by the timing gears 25, transmitting motion through the shaft 26, to the armature of the electric machine. The one-way clutch is included in the front end housing of the dynamo-electric-machine 24, which may be 80 of the same type as that shown and described in the co-pending applications heretofore referred to. This clutch permits the armature of the electric machine to operate free of the shaft 26, at such times as the shaft 85 26 is rotating at a less speed than the armature. However, as soon as the speed of the shaft 26 equals or becomes greater than the armature, the clutch will couple up the armature and the shaft 26, whereby the machine 90 will be operated as a generator, being driven by the engine. This operation of the armature will tend to generate current which will flow through the following circuit: from the generator brush 104, through the wire 95 93, contact plates 46 and 45, wire 97, where a portion of the current will tend to flow through the iron wire shunt 106, while the remainder of the current will flow through the wire 98, to the point 107, where a further division of the current will be made and a part thereof will flow through the shunt field 99, through the wire 100, to the opposite generator brush 75. The remainder 105 of the current will pass through the auxiliary series winding 108, whose windings are opposed in direction to those of the shunt windings 99, through the wire 109, to the wire 110, which connects with the cut-out 110 relay or current interrupter 112.

This relay, has for its function to prevent the flow of current from the battery, back through the electric machine, at such times as the voltage across the terminals of the machine is less than the voltage across the 115 terminals of the battery.

It will be appreciated that when the generator starts to operate, the voltage will be comparatively low, and as a general rule less than the voltage across the terminals of the 120 battery. For this reason, the current must first build up in the cut-out relay, which will remain open until the voltage of said current is greater than the battery voltage.

The flow of current from the wire 110 125 will therefore initially pass through the fine winding 113, to the ground connection 113^a, thus completing its circuit.

Now, as soon as the cut-out relay device is 130 energized that it will attract the ar-

ture 114, to close the contact plates 115 and 116, the current will flow through the heavy winding 117, through the wire 118, to the wire 91, across the battery 90, to the ground connection 95, and back across the generator.

As has been already stated, it is extremely desirable to effect a quick "building up" of the generator so that it will immediately, upon starting to operate, commence to charge the battery. This is assisted in the present instance by inserting an iron wire shunt 106 in such a manner as to short circuit the auxiliary or opposed series winding of the generator circuit, so that most of the current will initially pass through this shunt rather than through the series winding, thus permitting the voltage of the shunt field to rise rapidly.

However, as soon as the iron wire 106 begins to heat up, its resistance will also tend to increase and this will divert the flow of current through the opposed series winding, until such a time as a balancing effect is secured in the generator field windings. A similar arrangement of iron wire resistance is described more in detail in the Patent 1,171,055, above referred to.

In the present invention, it will of course be understood that the proportioning of the windings and the conductivity thereof will be arranged so as to produce the most efficient machines for the purposes desired, and it will also be understood that the sequence of operations and the relative timing thereof will be effected by the formation and arrangement of the mechanical elements in any suitable manner.

From the preceding description, it will be seen that the various field windings and armature windings are differently selected, according to the desired operative condition.

That is, for the slow initial starting movement (in which the coupling between engine and motor is effected), the shunt field winding 99 is used; and at this time the electric machine acts as a motor using the armature windings which are ordinarily used as the generator-armature windings.

Secondly, for the engine cranking movement, the heavy series field winding 101 is used, assisted by the shunt field winding 99; and during this period, the electric machine is acting as a series motor with high torque, the armature windings now being the heavy motor-armature windings, (the circuit through the generator-armature windings now being broken).

Thirdly, for the generating operation, the shunt field winding 99 is used, but opposed by the auxiliary series field winding 108; and in this generating period the generator-armature windings are used.

And the selection of these various field and armature windings is brought about by aid of the two switches referred to, viz.

the brush-lifting switch, and the outside switch (comprising the contacts 45, 46 and 47) both of which switches are operated from the common operating member or pedal 27.

The ignition system which formed a part of the original description in the present application, now forms the subject matter of a divisional application, Serial No. 80,877, filed February 28, 1916.

While the form of mechanism herein shown and described constitutes a preferred form of embodiment of the invention, it is to be understood that other forms might be adopted, all coming within the scope of the claims which follow.

What we claim is as follows:

1. In an engine starting system, the combination with an engine, a motor-generator, and a battery, with connecting devices between the motor-generator and the engine; of two sets of armature windings for the motor-generator, one a motor-armature and the other a generator-armature winding; a shunt field winding and two separate series field windings; and means for selecting the shunt field winding and one of the series field windings together with the motor-armature winding for cranking the engine by the motor, and for selecting the shunt field winding and the other series field winding together with the generator-armature winding for generating, said selecting means also having provisions for breaking the main generating circuit as an accompaniment to the making of the motor circuit for the cranking operation.

2. In an engine starting system, the combination with an engine, a motor-generator, and an accumulator, with connecting devices between the motor-generator and the engine; a shunt field winding and two separate series field windings; and a common operating member for controlling said connecting devices to connect the motor-generator with the engine, and likewise for selecting the shunt winding and one of the series windings for cranking the engine by the motor, and for selecting the shunt winding and the other series winding for generating.

3. In an engine starting system, the combination with an engine, a motor-generator, and a battery, with connecting devices between the motor-generator and the engine; of two sets of armature windings for the motor-generator, one a motor-armature and the other a generator-armature winding; a shunt field winding and two separate series field windings; a brush lifting switch in the circuit of the motor-armature winding, adapted to make and break the motor circuit; an additional switch device for controlling the generator circuit and the generator field winding; and a common operating member for controlling the opera-

tion of the brush lifting switch and the additional switch to select the shunt field winding and one of the series field windings for the motor operation, and to select the shunt field winding with the other series field winding for the generating operation.

4. In an engine starting system, the combination with an engine, a motor-generator, and an accumulator, with connecting devices between the motor-generator and the engine; a shunt field winding and two separate series field windings; and means for selecting the shunt winding and one of the series windings for cranking the engine by the motor, and for selecting the shunt winding and the other series winding for generating, with provisions for preliminarily selecting the shunt field winding for giving the motor-generator an initial movement to facilitate enmeshment of the said connecting devices.

5. In an engine starting system, the combination with an engine, a motor-generator, and a battery, with connecting devices between the motor-generator and the engine; of two sets of armature windings for the motor-generator, one a motor-armature and the other a generator-armature winding; a shunt field winding and two separate series field windings; and means for selecting the shunt field winding and one of the series field windings together with the motor-armature winding for cranking the engine by the motor, and for selecting the shunt field winding and the other series field winding together with the generator-armature winding for generating, with provisions for preliminarily selecting the shunt field winding and the generator-armature winding for giving the motor-generator an initial movement to facilitate enmeshment of the said connecting devices.

6. In an engine starting device, the combination with an engine and a starting device therefor, comprising a dynamo-electric machine having opposed shunt and series windings to be brought into use when the machine is operated as a generator, and an independent series winding to be brought into use when the machine is to operate as a motor for starting purposes; means for coupling the engine and starting device together for starting purposes; an accumulator having connections adapted to be made with the generator windings and with the motor windings; and controlling mechanism for shifting said coupling means to connect the engine and starting device together for starting purposes, and to concurrently connect the accumulator with the independent series winding of the dynamo-electric machine, whereby said machine will operate as a motor.

7. In an engine starting device, the combination with an engine and a starting de-

vice therefor, comprising a dynamo-electric machine having a series winding to be brought into use when the machine is to be operated as a motor; and an oppositely wound shunt and series winding adapted to be brought into use when the machine is to be operated as a generator; means for mechanically connecting the engine and the machine together for starting purposes; an accumulator adapted to be electrically connected with either the motor or generator windings of the machine; means for normally dis-establishing the electrical connection between the accumulator and the motor windings; switch means for normally establishing connection between the accumulator and generator windings; a supplemental switch in said generator circuit; and a main operating member for controlling the mechanical connections between the engine and dynamo-electric-machine, and having provisions for mechanically operating the supplemental switch mechanism, so that the accumulator may be connected with the generator, whereby the machine will operate as a shunt wound motor, previous to its actual starting operation.

8. In a starting device for engines, the combination with an engine and a starting device therefor, comprising a dynamo-electric machine having opposed shunt and series windings adapted to be brought into operation when the machine is to operate as a generator; and an independent series winding adapted to be brought into operation when the machine is to operate as a motor for starting purposes; an accumulator having connections adapted to be made with the generator windings and the motor windings; and means for connecting certain of the windings of the generator to the accumulator, whereby the machine will be operated as a motor, by passing current through the shunt winding.

9. In an engine starting device, the combination with an engine and a starting device therefor, comprising a dynamo-electric machine, having oppositely wound shunt and series windings adapted to be brought into use when the machine is to operate as a generator; and an independent series winding adapted to be brought into use when the machine is to operate as a motor for starting purposes; a source of current having motor and generator circuit connections with the electric machine, including commutator brushes, one of said brushes being normally positioned to break the motor circuit; independent switch mechanisms included in said circuit connections, one of which normally maintains the generator circuit closed, another of which is normally open; means for mechanically connecting the electric machine as a motor to the engine for starting purposes; and a

main operating member having a sequence of operations to initially close the normally opened switch mechanism contained in the generator circuit, whereby current will pass through the shunt winding only of the generator to operate the machine as a motor at an initial speed; and secondly to effect the shifting of the coupling means to mechanically connect the electric machine to the engine for starting purposes, and thirdly to operate relative to the normally closed switch in the generator circuit to open the same and thus break the normally closed generator circuit, and fourthly to operate relative to the displaced brush to permit the same to complete the motor circuit for starting purposes.

In testimony whereof we affix our signatures in the presence of two subscribing witnesses.
